UNITED STATES PATENT OFFICE.

CHARLES V. MCINTIRE, OF EAST ORANGE, NEW JERSEY, ASSIGNOR TO CONSOLIDATION COAL PRODUCTS COMPANY, OF WILMINGTON, DELAWARE, A CORPORATION OF DELAWARE.

RETORT FURNACE.

Application filed July 15, 1924. Serial No. 726,217.

My present invention consists in improvements in the retort of my prior Patent No. 1,457,083 devised with the general object of improving its mechanical construction and 5 facilitating the maintenance of tight joints between the interior of the retort and its heating flues.

The various features of novelty which characterize my invention are pointed out 10 with particularity in the claims annexed to and forming a part of this specification. For a better understanding of the invention, however, and the advantages possessed by it, reference should be had to the accompanying 15 drawings and descriptive matter in which I have illustrated and described a preferred embodiment of the invention.

Of the drawings:

- 20 Fig. 1 is a transverse vertical section;
- Fig. 2 is a partial section on the line 2—2 of Fig. 1;
- Fig. 3 is a partial section on the line 3—3 of Fig. 1;
- Fig. 4 is a partial section on the line 4—4 of Fig. 1;
- Fig. 5 is a partial section on the line 5—5 of Fig. 1; and

Fig. 6 is a sectional elevation of the retort.

The retort A shown in the drawings is horizontally disposed, though its axis need not be exactly horizontal, and has a curved bottom wall formed of metal sections shaped to provide circumferentially extending internal and external grooves *b* and *b'* respectively. 30 The outer edges of the external grooves *b'* are closed by a cylindrical wall C formed of fire bricks, on which the metal sections rest and the external grooves *b'* serve as heating flues receiving gas and air for combustion 35 at their ends and discharging products of

combustion into an outlet channel C¹⁰ longitudinally disposed beneath the retort. The grooves *b* and *b'* are all curved about the same axis so that the internal grooves *b* may 40 be swept by the blades M' of an agitator M oscillated through an arc of approximately 270° by the gear M² driven by the rack M³ connected to the piston of a hydraulic motor M⁴ about an axis coincident with the axes 45 of curvature of the grooves *b* and *b'*. In so far as above described, the retort is similar in construction and in its intended mode of operation to the retort of my prior Patent No. 1,457,083, although the agitating mech-

anism employed is of the character illustrated 55 in my prior Patent No. 1,479,827, granted January 8, 1924.

In accordance with the present invention, the metallic bottom wall of the retort proper is formed by sections B and BA, which are 60 made of cast metal, but preferably are of one or another of the highly refractory metallic alloys now coming into use for high temperature work. The sections B and BA are channel shaped in cross section and the wall of each groove *b'* is formed by a central or bottom section BA and two end sections B. Each section BA is provided at its ends with tongue or flange portions which extend telescopically into the adjacent ends of the corresponding end sections B, the flange or tongue portions being shaped to provide joints B², which may be sealed by luting them with a refractory cement inserted through the open 70 upper ends of the sections B. The outer edges B' of the sections B and BA are received in the circumferentially extending grooves C' formed in the concave face of the fire brick housing body C. Each groove C', except the two end grooves, receives the edges B' at the adjacent sides of two adjacent flues *b'*, and advantageously, the edge portion B' of the sections BA and of the body portions of the sections BA are radial so that the sections B and BA enclosing adjacent flues *b'*, fit snugly together and provide radially elongated joints, whereby the tendency to gas leakage through the joints is minimized. Advantageously, as shown in Fig. 3, the sides 80 of the sections B and BA are curved so that the bottoms of the grooves *b* are rounded, as this facilitates the operation of the agitating means (not shown) by which these grooves are swept.

At its upper end each section B is contracted in width to provide space between adjacent sections B for the sides E' of end members E, which may be cast of the same metal as the section B and BA, and have inner end portions generally similar in cross section to the parts B and BA. Advantageously, as shown, the brick housing body C is bevelled off at its upper edges to provide flat surfaces C² over which the end members E, and the outer ends of the sections B project. The grooves C' are extended along the seats C², and each groove C' is bifurcated at its upper end, as seen in Fig. 2, each bifurcation com-

5 municating with a transverse groove C³, which also communicates with the bifurcation at the opposite side of the same flue b'. The bottom portion of each member E is partially closed by an integral portion E² provided at its inner edge with a down-turned flange E³ which is received in the corresponding groove C³ and merges into the lower portions of the side edges E'. Each member E 10 overlaps the outer end of the corresponding section B and the parts are relatively shaped and arranged to provide a joint EB, which can be sealed as are the joints B² by a suitable luting material inserted through the 15 open outer end of the member E when the aperture stop-plate or plug H, normally closing the member E, is removed.

As shown, the refractory housing body portion C is surrounded by a metal casing D, 20 the upper edged D' of which are inwardly inclined to fit against the correspondingly inclined portions of the brick work C, so that they extend transversely to the seat portions C². These upper edge portions D' of the casing D are provided with apertures for the box-like body portions of the members E and are formed with flanges at the margins of said apertures to provide a space D² for luting material, by which the joints between 30 the members E and the portions D' are sealed.

The formation of the metal walls for the flues b' out of sections B and BA, as described, permit of thermal expansion and contraction of the sections without creating disruptive strains, but the thermal elongation of the sections which occurs on an increase in temperature, tends to produce open joints between the sections on a subsequent reduction in temperature unless suitable provisions are 40 made for applying pressure to the outer ends of the sections BA tending to hold the sections snugly together. This pressure is applied, in accordance with the present invention, by means of tension springs G acting 45 between brackets D³ carried by the housing casing D, and tension bolts F pivotally connected at E⁴ to the outer ends of the members E. The top wall of the retort is formed by a curved metal body DA, which rests on the extreme upper edges of the armor casing D. Advantageously, as shown, the adjacent edges of the members D and DA are provided with outwardly extending flanges, shaped to provide a space D¹⁰ for the reception of a 50 suitable luting material for sealing the joint. The adjacent flanges of the members D and DA may be bolted or otherwise clamped together, though the weight of the top member DA may be relied upon to hold the latter 55 in place.

The outer ends of the box-like portions of the members E, are advantageously closed by flanged cast metal parts H fitting snugly in the appropriate members E. The joints between the parts H and the members E may 60

be readily luted to prevent leakage. Advantageously, each member H, is formed with a peep hole H' normally closed by a plug (not shown), and is also formed with an aperture to receive the corresponding burner nozzle I. The burner nozzles I (as shown) each receive a combustible mixture of air and combustible gas through individual valved branches L' and K' from air and gas supply mains L and K respectively. 70 75

The coal to be carbonized or other material treated, is fed into the retort by a screw conveyor N. The end wall O is formed with an outlet O' for gases of distillation connected by gas piping O² to the outlet main O³. A second outlet P' in the end wall O for the discharge of the semi-coke or other non-volatile residue of the material treated opens into a discharge spout P provided with doors P² and P³ which are gravity closed and permit the discharge of the semi-coke or other residue while preventing the outflow of gas through the opening P'. 80 85

My improved retort structure is characterized by its mechanical simplicity, effectiveness and its ability to withstand the destructive forces to which it is subjected in operation. It is further characterized by the character and effectiveness of the provisions made for maintaining tight joints, and by the 90 accessibility of the joints for re-luting when this is necessary or desirable. 95

Having now described my invention, what I claim as new and desire to secure by Letters Patent, is: 100

1. A horizontally disposed retort comprising a bottom part of refractory material having a trough shaped upper surface with transverse grooves formed therein, a metallic lining for said surface formed of arc shaped 105 sections of inverted trough shape in transverse section, with the outer edges of the trough sides received in said grooves, and means for passing heating gases through the flue spaces formed within said sections above 110 said surface.

2. A horizontally disposed retort comprising a bottom part of refractory material, a metallic lining for the upper surface of said part comprising metallic sections of inverted trough shape in transverse section which co-operate with said surface to define heating flues, the top wall of each such flue being formed by a plurality of said sections connected end to end and each pair of sections so connected having telescopic portions co-operating to form a joint which can be luted with material inserted through the end of the flue. 115 120

3. A horizontally disposed retort comprising a bottom part of refractory material having a trough shaped upper surface with transverse grooves formed therein and extending across said surface and each forked adjacent the side edges of said surface and grooves 125 130

- transverse to the first mentioned grooves each connecting the adjacent forks of an adjacent pair of the first mentioned grooves, a metallic lining for said surface comprising arc shaped sections of inverted trough shape in transverse section co-operating with said surface to define portions of flues with the outer edges of the trough sides received in the first mentioned grooves and metallic parts forming 5 the ends of said flues comprising portions extending in the bifurcated ends of the first mentioned grooves and into said transverse grooves.
4. A horizontally disposed retort comprising a bottom part of refractory material having a concave upper surface, a metallic lining for said surface comprising arc shaped sections of inverted trough shape in transverse section which co-operates with said surface 10 to define curved heating flues, the top wall of each such flue being formed by a plurality of said sections connected end to end and each pair of sections so connected having telescopic portions co-operating to form a joint 15 which can be luted with material inserted through the end of the flue.
5. A horizontally disposed retort comprising a bottom part of refractory material, a lining for said bottom part formed of metal parts each of inverted trough shape in transverse section and co-operating with said surface to define a portion of a heating flue and metallic conduit parts extending through the 20 side walls of the retort and co-operating with said metal parts and bottom part to form the end portions of said flues.
6. A horizontally disposed retort comprising a bottom part of refractory material, a lining for said bottom part formed of metal parts each of inverted trough shape in transverse section and co-operating with said surface to define a portion of a heating flue, metallic conduit parts extending through the side walls of the retort and each formed with 25 an inner end portion of inverted trough shape which overlaps one end of one of said first mentioned metal parts.
7. A horizontally disposed retort comprising a bottom part of refractory material, a lining for said bottom part formed of metal parts each of inverted trough shape in transverse section and co-operating with said surface to define a portion of a heating flue, metallic conduit parts extending through the side walls of the retort and each formed with 30 an inner end portion of inverted trough shape which overlaps one end of one of said first mentioned metal parts.
- an inner end portion of inverted trough shape which overlaps one end of one of said first mentioned metal parts, and means external to the retort engaging said conduit parts and exerting a yielding force against said first mentioned metal parts tending to contract the length of the flues formed by said first mentioned metal parts and to press the latter against said bottom part.
8. A horizontally disposed retort comprising a bottom part of refractory material, a lining for said bottom part formed of elongated metal parts each of inverted trough shape in transverse section and co-operating with said surface to define a portion of a heating flue, metallic conduit parts extending through the side walls of the retort and each formed with an inner end portion of inverted trough shape which overlaps one end of one of said first mentioned metal parts, and removable closures for the passageways through said conduit parts.
9. A horizontally disposed retort comprising a bottom part of refractory material, a lining for said bottom part formed of elongated metal parts each of inverted trough shape in transverse section and co-operating with said surface to define a portion of a heating flue, metallic conduit parts extending through the side walls of the retort and each formed with an inner end portion of inverted trough shape which overlaps one end of one of said first mentioned metal parts, and removable closures for the passageways through said conduit parts formed with peep holes.
10. A horizontally disposed retort comprising a bottom part of refractory material, a lining for said bottom part formed of elongated metal parts each of inverted trough shape in transverse section and co-operating with said surface to define a portion of a heating flue, metallic conduit parts extending through the side walls of the retort and each formed with an inner end portion of inverted trough shape which overlaps one end of one of said first mentioned metal parts, and removable closures for the passageways through said conduit parts, and means for passing gas and air for its combustion into said passageways.

Signed at Fairmont, in the county of Marion and State of West Virginia, this 8th day of July A. D. 1924.

CHARLES V. McINTIRE.
